UNITED STATES PATENT OFFICE.

GEORGE W. HOLLY, OF PALOALTO, CALIFORNIA, ASSIGNOR OF ONE-HALF
TO J. F. PARKINSON, OF PALOALTO, CALIFORNIA.

DOOR-HANGER.

SPECIFICATION forming part of Letters Patent No. 733,041, dated July 7, 1903.

Application filed September 24, 1901. Serial No. 76,374. (No model.)

To all whom it may concern:

Be it known that I, GEORGE W. HOLLY, a citizen of the United States, residing at Palo-alto, in the county of Santa Clara and State 5 of California, have invented new and useful Improvements in Hanging Sliding Doors, of which the following is a specification.

This invention relates to an improved means for hanging sliding doors; and the object 10 thereof is to provide a cheap, durable, and efficient means for hanging doors whereby they will be prevented from sagging or binding within the pocket formed by the partition-walls of the structure in which they are 15 hung.

Further objects, as well as the peculiar details of construction, will be clearly described hereinafter and defined in the appended claims.

20 In the drawings, Figure 1 represents a side elevation of the door hung in accordance with my invention and illustrated as being closed or projected forward. Fig. 2 is similar view showing the door within the pocket.

25 Fig. 3 is a like view, the door being illustrated as partially closed. Fig. 4 is a top plan view of the door-frame. Fig. 5 is a detail view of the means for securing the lever to the door. Fig. 6 is a sectional view through the same.

30 Fig. 7 is a rear elevation of the hanger-securing means. Fig. 8 is a slightly-modified form of the hanging-lever; and Fig. 9 is a side elevation of a door-frame, showing two doors therein, one being retracted and the other 35 projected.

1 designates a frame provided with end battens 2 and 3 and vertical battens 4 and 5, between which the levers to which the door is hung is secured. The door is slidably secured 40 within the frame, which frame is adapted to be removably fastened in the pocket formed by partitions of the wall of the structure in which the door is used, so that the frame and door may be removed, if desired.

45 6 and 7 designate two sets of toggle-levers, which are suspended from the top of the frame 1 by pivotal connections 8 and 9. (Best shown in Fig. 3.) The two sets of levers are secured to each other and to the door, as will be hereinafter explained. Two similar sets of levers 10 and 11 are secured to the bottom of the frame by pivotal connections 12 and 13 and

are also pivotally secured to the lower portion of the door. The toggle-levers 6 are pivotally connected to the levers 10 by a link 55 connection 14, while the set designated by the reference-numeral 7 is pivotally connected to the set 11 by a similar connection 15 in order to strengthen the same and provide for perfect unison of action. It will be noticed that 60 the connections 14 and 15 cross one another, causing the top levers to alternate with the lower sets, so that one set of levers from the top and bottom, respectively, will be folded against the rear of the frame when the door 65 is retracted in the pocket. The opposite sets will be folded against the door when said door is projected from the pocket to close the opening between the two arms.

One of the features of this invention is to 70 also provide means for swinging the door outward. In order to do this, I arrange a plate 16 on the rear edge of the door near the top, to which is hinged a similar plate 17, provided with right-angular longitudinally-arranged 75 flanges 18 and 19, between which is pivoted a block 20, provided with a projecting pin 21, to which one arm, respectively, of the toggle-levers 6 and 7 are pivotally secured. A similar device, as shown in Fig. 10, is secured 80 to the lower edge of the door and is pivotally connected to one arm, respectively, of the toggle-levers 11 and 10. The door is thus suspended within the frame and moves freely back and forth, the entire weight thereof being 85 provided for by the levers.

In order to prevent sagging of the free end of the door, I provide a threaded pin 22, having a head 23, adapted to be loosely seated in a recess formed in the rear face of the 90 plate 17 of the hinge and to project through the opening 24 therein and to engage a screw-thread opening in the block 20, whereby by inserting a pin through the transverse opening in said pin 22 the block may be adjusted to take up any sagging of the door. The door may also be swung on the hinges formed by the plates 16 and 17, as it is advantageous to use said door in this manner rather than by sliding the same.

100 In Fig. 8 I have illustrated a modified form of levers, in which 27 and 28 designate two T-shaped bars connected by cross-links 29 and 30. These may be used in lieu of the tog-

gle-levers above referred to; but I prefer the form illustrated in Figs. 1, 2, and 3.

In Fig. 9 I have illustrated a pair of sliding doors fitted in a suitable frame. One of the doors is shown as retracted and the other one projected.

It will thus be seen that I have provided an efficient means for hanging doors, and the objections ordinarily raised in regard to this class of devices will be overcome. I also desire to particularly point out the peculiar novel manner of providing a combined swinging and sliding door whereby either type of door is provided without altering the construction of the device.

In order to enable others skilled in the art to which this invention relates to make and use the same, I have specifically described what to me at this time appears to be the very best means of accomplishing the desired result. However, I would have it understood that I do not limit myself to the exact details of construction shown, but reserve the right to make such slight changes and alterations as would suggest themselves from time to time without departing from the spirit thereof.

Having thus fully described my invention, what I claim, and desire to secure by Letters Patent, is—

1. In a door-hanger, the combination with

a frame and a door, of toggle-levers adapted to project and retract the door within the frame, a hinged connection carried by the door and a block adjustably carried by the hinged connection and connected to the toggle-levers, whereby the said door may swing laterally with relation to the frame. 35

2. In a door-hanger for a sliding and swinging door, the combination with a frame and door, of toggle-levers pivotally secured to the top and bottom of said frame, hinges carried by said door, adjustable blocks pivotally secured to the hinges, and means for pivotally securing the levers to the blocks. 40

3. In a door-hanger for a sliding and swinging door, the combination with a frame and door, of toggle-levers pivotally secured to the top and bottom of said frame, link connections connected to said levers, hinges carried by said door, a block pivoted to one leaf of each hinge, an adjusting-screw adapted to regulate the pitch of the block, and means for pivotally securing the levers to said block. 45

In testimony whereof I affix my signature in presence of two witnesses.

GEORGE W. HOLLY.
